PEDESTAL STRUCTURE

Samuel H. Frankel, Chicago, Ill., assignor, by
mesne assignments, to Helene Curtis Industries,
Inc., a corporation of Illinois

Application July 12, 1945, Serial No. 604,562

5 Claims. (Cl. 248—194)

1

This invention relates to improvements in pedestal structures and more particularly concerns new and improved means for securing into a fixed unit the various components at the base of a pedestal of the kind which is especially adapted for use with hair dryers and the like.

An important object of the invention is to provide a new and improved pedestal structure which is simple and economical to produce and assemble and which is quite efficient and durable in use.

Another object of the invention is to provide a novel pedestal structure which affords convenient and simple means for setting up the pedestal base from a knock-down condition.

Still another object of the invention is to provide new and improved means in a pedestal base structure for efficiently connecting together the various parts of the assembly.

Other objects, features, and advantages of the invention will be readily apparent from the following detailed description of a preferred embodiment of the invention, taken in conjunction with the accompanying one sheet of drawings, in which:

Fig. 1 is a perspective view of the base portion of a pedestal embodying the features of the invention.

Fig. 2 is an enlarged vertical sectional detail view through the pedestal structure taken substantially in the plane of line 2—2 of Fig. 1.

Fig. 3 is a horizontal sectional detail view taken along the line 3—3 of Fig. 2.

Fig. 4 is a perspective view of the novel connector through the medium of which the various parts of the base portion of the pedestal are secured together.

Certain portable apparatus customarily equipped with pedestal structure, such as the hair dryers employed in beauty shops, is shipped from the factory or warehouse in a knock-down condition and must then be set up at the point of use or display. Since the persons who must do the setting up are often inexperienced and in many instances lacking in mechanical aptitude, it is highly desirable that the components to be assembled be as few and simple and as fool-proof in construction as practicable. Once set up, the structure should require no adjustment, and practically no further attention or servicing throughout the life of the apparatus, or at least during very long periods of use.

A construction meeting these requirements and incorporating my invention may comprise a tubular pedestal or standard 10 and a set of preferably identical radially extending legs 11 which may be

equipped with casters 12 for ready portability. Each of the legs 11 preferably is L-shaped, standing upright in assembly with the horizontal arms radiating out from the standard 10 and carrying the casters 12 while the remaining arms extend upwardly into engagement with a standard-encircling connecting cap 13 to which they are secured by means such as screws 14 (Fig. 1). The lower end portion of the standard 10 extends down within the cage provided by the vertical arms of the legs and is joined through the medium of a connector 15 with shoulders 17 extending from the adjacent angles of the legs. In addition, the connector 15 may serve as a medium for supporting and securing within the assembly a coiled counterbalance spring 18 and a stabilizer post 19 (Figs. 2 and 3) concentrically disposed within the standard 10. For a more detailed description of the latter features reference may be had to my copending application Serial No. 604,563 filed July 12, 1945.

According to the present invention, the connector 15 may be a casting or the like but preferably comprises a simple sheet metal stamping of appropriate thickness which in one sense may be considered as a disk supporting and connecting the various parts of the assembly, and which for efficient, durability, and simplicity in construction is formed with a central, in this instance cylindrical, embossment 20. The result is a symmetrical substantially hat shaped member comprising a radial flange 21 about a body or wall 22 defining the boss 20, and a slotted crown 23 on the boss parallel to the flange 21 (Fig. 4).

Attachment of the leg shoulders 17 to the connector 15 is effected on the upper face of the flange 21. Screws 24 extend up through screw holes 25 in the flange 21 and into tapped screw holes 26 in the respective leg shoulders 17. Lockwashers 27 may be interposed between the heads of the screws 24 and the adjacent faces of the flange 21. For symmetry in structure and appearance, the leg shoulders 17 are preferably proportioned to occupy substantially the entire flange 21 and entirely surround the embossment 20. Thus, as best seen in Fig. 3, where, as in the present instance, there are four of the legs 11, the shoulders 17 are formed as quadrants cooperating to complete a circle about the embossment 20 and each secured to the flange 21 by two of the screws 24. If desired, of course, one of the screws may be replaced by a dowel or a locating pin or the connector or the pedestal legs may be formed with lugs or projections interfitting in appropriate slots or sockets; but these equi-

alents are probably less economical than the use of a pair of screws as illustrated. The result is a strong, wobble-proof connection for the legs which will effectually resist cantilever and lateral displacing forces to which the legs are inevitably subjected in the use of the apparatus.

Besides serving as a strong reinforcement for the flange 21 due to the rigid right angular relationship thereof, the embossment wall 22 serves as a centering and connecting device fitting snugly within the lower end of the standard 10 (Fig. 2). To this end, of course, the diameter of the embossment body 22 is calculated to approximate and slidably interfit reasonably snugly with the internal diameter of the tube of the standard 10. A permanent assembled relationship of the standard 10 with the embossment 20 may be effected in any preferred manner as for example by means of rivets 28 extending through registering apertures 29 and 30 in the cylindrical embossment wall 22 and the contiguous wall of the tube 10, respectively.

In the present instance, the crown 23 serves more or less as a platform within the standard 10 against which the lower end of the spring 18 abuts and to which the stabilizer post 19 is secured in centered relation. By preference attachment of the post 19 to the crown 23 is effected by means of lugs 31 which are integral with the lower end of the post and extend through appropriate slots 32 in the crown, being bent over toward the lower face of the crown.

It will thus be apparent that the connector 15 may be assembled in a factory unit with the standard 10, the spring 18 and the post 19. With this preassembled unit the legs 11 can be assembled quickly, positively and in fool-proof manner and secured in place on the connector flange 21 by the simple expedient of the screws 24.

While I have illustrated and described a certain preferred embodiment of my invention, it is to be understood that I do not thereby intend to limit my invention to the specific form disclosed, but contemplate that various modifications, substitutions, and alternative constructions may be effected without departing from the spirit and scope of the invention as defined in the appended claims.

I claim:

1. In combination in a pedestal structure of the character described, an upright hollow standard, a plurality of substantially L-shaped legs having vertically and horizontally extending portions and disposed with their apexes adjacent the bottom of the pedestal, means connecting the upper portions of the legs together adjacent to the standard, a centrally embossed connector having the embossment secured within the lower end of the standard and providing a horizontal flange projecting laterally from the lower end of the standard, and shoulders at the apexes of the legs secured to said flange.

2. In combination in a pedestal structure, an

upright standard, a plurality of legs having upstanding arms connected together about the standard, the lower end of the standard being adjacent to the lower ends of the upstanding arms, a connector for the lower end of the standard and the legs comprising a disk member, and means for securing the standard and the corner portions of said legs to the disk member.

3. In combination in a pedestal structure of the character described, a vertical standard having a downwardly opening hollow base end, a plurality of legs, a centrally embossed disk member having an upstanding portion fitting snugly within said hollow base end and presenting a flange extending laterally beyond the end of the standard to limit insertion of the upstanding portion, means for securing the connector and the standard together, and means for securing said legs to said flange.

4. In combination in a pedestal structure of the character described, a vertical standard having a downwardly opening hollow base end, a plurality of legs, a centrally embossed disk member having an upstanding portion fitted snugly within said hollow base end and presenting a flange extending laterally beyond the end of the standard, the embossment having a crown formed with a plurality of perforations, means for securing the connector and the standard together, mechanism within the standard having means secured to said crown through said perforations, and means for securing said legs to said flange.

5. In combination in a pedestal structure of the character described, a tubular standard, operating mechanism within the standard, a plurality of legs serving as a base for the standard, and means for connecting the standard and the legs together comprising a centrally embossed disk member having the embossed portion thereof extending in closely cooperative relation into the base end of the standard and providing a lateral flange for cooperation with the legs, said embossed portion being formed with a crown providing a platform for supporting said operating mechanism within the standard.
